(57) **CLAIM**

We claim the ornamental design for a wheel for a model vehicle, as shown and described.

DESCRIPTION

FIG. 1 is an upper, left, rear perspective view of a wheel for a model vehicle;

FIG. 2 is front elevation view thereof, the rear elevation view being a mirror image thereof;

FIG. 3 is a right side elevation view thereof;

FIG. 4 is a left side elevation view thereof;

FIG. 5 is a top plan view thereof, the bottom plan view being a mirror image thereof; and,

FIG. 6 is an upper, right, rear perspective view.

In the drawings, the broken line showing of features of the wheel for a model vehicle illustrate portions of the tire for a model vehicle that form no part of the claimed design. In the drawings, only the front plan view and top plan view are shown. The corresponding rear plan view and bottom plan view are mirror images of the front plan view and top plan view and are included in the scope of the claim.
